UNITED STATES PATENT OFFICE

2,480,597

DETACHABLE WHEEL GOLF CLUB CARRIER

Carl Wilbur Nelson, Racine, Wis.

Application January 26, 1948, Serial No. 4,259

5 Claims. (Cl. 280—49)

1

This invention relates to improvements in detachable wheel golf club carriers.

An object of the invention is to provide an improved detachable wheel golf club carrier.

Another object of the invention is to provide an improved detachable wheel golf club carrier whereon a set of golf clubs may be supported in arcuate parallel relation upon the exterior surface of said carrier.

A further object of the invention is to provide an improved detachable wheel supported golf club carrier including a light frame having vertically spaced notched golf club supporting and clamping strips disposed thereon for supporting the golf clubs in parallel relation upon the exterior surface of said carrier.

A still further object of the invention is to provide an improved detachable wheel supported golf club carrier including a light weight tubular metal frame having one or more compartments built therein and having closure members therefor together with vertically spaced notched arcuate golf club supporting and clamping strips disposed on said compartments for supporting a set of golf clubs in parallel relation upon the exterior surface thereof.

Another object of the invention is to provide an improved form of detachable wheel golf club carrier which will support a set of golf clubs on the exterior surface thereof, said carrier being highly efficient in operation, and relatively inexpensive to manufacture and produce.

Other objects will appear as the description proceeds.

In the accompanying drawings which form a part of this application,

Figure 1 is a perspective view of the improved detachable wheel golf club carrier showing a set of clubs supported thereon;

Figure 2 is a perspective view of the improved detachable wheel golf club carrier shown in rest position with all but two of the golf clubs removed;

Figure 3 is a perspective view of the rear of a detachable wheel golf club carrier showing the compartment closures open and one wheel removed and stored in the lower compartment;

Figure 4 is a sectional view taken on the line 4—4 of Figure 3;

Figure 5 is an enlarged fragmentary horizontal sectional view of a wheel spindle shown in operative position, and contiguous structure;

Figure 6 is a perspective view of the tubular carrier frame;

Figure 7 is an enlarged detailed view of por-

2

tions of the frame and wheel supporting structure, the said structure being illustrated as partly withdrawn from the frame;

Figure 8 is a grouped view of the channeled or notched golf club supporting bands or strips;

Figure 9 is a fragmentary three dimensional view of the above mentioned wheel supporting structure;

Figure 10 is a view similar to Figure 5 and showing a modified form of the same structure;

Figure 11 is a slightly diagrammatic view showing side arms of the frame in horizontal section and end views of modified forms of panels;

Figure 12 is a three dimensional view of the front panel comprising one of the four modified panels illustrated in Figure 11;

Figures 13 and 14 are longitudinal and transverse sectional views of the golf ball dispenser, taken on the respective section lines in Figure 3.

Like characters of reference are used throughout the following specification and the accompanying drawings to designate corresponding parts.

In carrying out the invention, there is provided an improved form of detachable wheel golf club carrier including a frame generally designated by the reference numeral 1 having an inverted U-shape tubular metal handle 2 with parallel elongated side arms 3 and 4 forming the front members of the carrier frame 1.

Transversely extending vertically spaced upper and lower arcuate tubular frame bracing members 5 and 6 are suitably secured at their opposite ends to the parallel side arms 3 and 4, as by welding.

Parallel vertically extending rear tubular frame members 9 and 10 are curved forwardly adjacent their upper ends as at 11 and 12, and are welded to the side arms 3 and 4.

Upper and lower transversely extending tubular reinforcing frame members 13 and 14 are welded at their opposite ends to the rear vertical frame members 9 and 10, and vertically spaced reinforcing frame members 15 and 16, and 18 and 17 are welded at their opposite ends between the arms or members 3 and 9, and 4 and 10, respectively, the members 15 and 17 being tubular and inserted through members 9 and 10 and partially through the members 3 and 4 as illustrated at 15 and 17.

An arcuate front panel 19 is secured between the side arms 3 and 4, and upper and lower elongated arcuate strips 20 and 21 of rubber or leather, or any other desired flexible material having a series of golf stick handle or shaft supporting

notches 22 formed in their front edges, are adapted to be suitably secured to said upper and lower edges of the arcuate front panel 19, by screws 7 inserted through the panel 19 and into the adjacent portions of the strips 20 and 21.

An upper shelf 23 having an arcuate forward edge 24 is disposed slightly below the bottom of the arcuate front panel 19 and serves to support the inwardly extending metal heads 25 of the metal headed clubs 26 when the handles or shanks 27 are supported in the spaced notches 22 in the arcuate club handle supporting strips 20 and 21. A lower shelf 28 is disposed at the lower end of the carrier frame 1 below the shelf 23, and notches 29 are cut in the arcuate forward edge 24 of the shelf 23 so that the wooden club heads 30 may be supported on the shelf 28 with their outer ends extending inwardly and the portions of the heads to which the shanks 31 are secured are disposed in the inverted V-shape notches 29 when the handles or shafts 32 are supported in the notches 22 in the arcuate strips 20 and 21. The notches 22 in the upper strip 20 may be uniform but the lower strip 21 will have larger notches 22' interposed between smaller notches 22'' to accommodate shank portions of wooden and iron headed clubs, respectively.

It will be seen that all of the metal head clubs and wood head clubs will be supported on the exterior surface of the arcuate front panel 19 in position for any club to be readily grasped and gently pulled loose from its supporting notches 22 when it is to be used. Likewise, the club may be just as readily replaced after it has been used.

Upper and lower compartments 33 and 34 will be formed by the front panel 19, the rear panel 39 and the side panels 35 and 36. A closure 37 for the upper compartment 33 will be hinged at 38 to the rear panel 39. A partition 40 will be disposed between the upper and lower compartments 33 and 34, and a closure 41 will be provided for the lower compartment 34, being supported by the hinges 42.

The front and rear panels and the side panels are all provided with interfitting scallops 43 which are arcuate transversely of the panels, so that the panels are sprung into position being further secured by screws 43', the scallops being apertured as at 43'' and the frame members being also apertured to receive these screws.

Openings 44 will be formed through the tubular members 9 and 10, aligned with the frame members 15 and 17, to receive the wheel supporting spindles 46 which carry the arcuate head members 47 to which the wheel axles 48 are also secured to extend at right angles to the supporting spindles 46.

Rubber tired disc wheels 49 and 50 are adapted to be rotatably supported upon the wheel axles 48, and the supporting spindles 46 may be quickly inserted in or withdrawn from the members 15 and 17 when the wheels 49 and 50 are to be placed in operative position, or are to be removed and stored in the lower compartment 34.

Various golf equipment, such as tees, score cards, pencils and shoes (not shown) may be received and stored in the upper compartment 33 and a specially designed golf ball dispenser, generally indicated at 56 in Figure 3, is mounted upon the closure 37 for the upper compartment. This dispenser 56 includes an endless tube 53 held to the closure 37 by brackets 60 and having an opening 62 to allow golf balls 64 to be inserted into and withdrawn from the tube. The tube may be slightly flexible and is slotted at 66 to allow inser-

tion of a finger for moving the balls toward the opening 62 and also to allow inspection as to the number of balls in the dispenser. The tube may have radially extending terminal portions 68 to which inflexible guard plates 70 are secured by rivets 72, at the edges of the opening 62.

In a modified form of this invention, the front panel 19' may be constructed as illustrated in Figures 11 and 12, the arcuate notched strips 20 and 21 being deleted and the front panel being press formed to provide upstanding integral spring clips 51 at the upper end and grooves 52 on an intermediate portion, while the shelf 23', having notches 29', is also integrally formed.

A modified form of wheel supporting means is illustrated in Figures 9 and 10, in which the supporting spindles 46' are extended through the head members 47' and enlarged and bent as at 53 to comprise axles 48'. Alignment pins 54 are provided on the inner faces of the head members 47 for engagement in apertures 55 in the frame members 10, these pins 54 and apertures 55 being shown in Figures 3 and 9, since these elements may be incorporated with the invention when either illustrated type of wheel supporting means is used.

From the foregoing description, it will be seen that there has been devised and provided a highly efficient form of detachable wheel golf club carrier which will be so constructed that the supporting wheels therefor may be readily removed and stored within the carrier when the same is not to be used, and may be quickly inserted in operative position when the carrier is to be used by the golfer and pulled or pushed over the golf course when playing golf.

It will be further seen that the improved detachable wheel golf club carrier is so formed that a complete set of metal and wood clubs may be supported exteriorly upon the outer surface of the carrier where a golfer or a caddie may readily see at a glance the club desired and remove it from its position upon said panel.

While the preferred embodiment of the present invention has been illustrated and described, it will be understood that it is not intended to limit the scope of the invention thereto, as many minor changes in detail of construction may be resorted to without departure from the spirit of the invention.

Having described the invention, what is claimed as new is:

1. A detachable wheel golf club carrier including a tubular frame having an inverted U-shape handle and depending parallel side arms forming the forward corner supports for said frame, said tubular frame members having arcuately forwardly extending upper ends secured to said side arms, tubular connecting braces between the lower ends of said arms and members, arcuate vertically spaced transversely extending tubular frame bracing members secured at their ends to said depending parallel side arms, an arcuate front panel supported by said last mentioned tubular frame bracing members, wheels detachably supported by said frame, notched vertically spaced arcuate transversely extending supporting strips secured to the upper and lower ends of said arcuate front panel, and vertically spaced upper and lower platforms disposed at the lower end of said arcuate front panel for respectively supporting the metal head and wood head golf clubs when their shafts or handles are received in said arcuate notched handle supporting strips 75 on the front surface of said arcuate front panel.

2. The subject matter as claimed in claim 1, said panel having inverted V-shaped wood club head positioning notches between said vertically spaced upper and lower platforms.

3. The subject matter as claimed in claim 1, said panel having inverted V-shaped wood club head positioning notches between said vertically spaced upper and lower platforms supported by the carrier frame at the rear of said arcuate front panel, and hinged closures for said platforms.

4. A detachable wheel golf club carrier including a tubular frame having an inverted U-shape handle and depending parallel side arms forming the forward corner supports for said frame, rear tubular frame members having arcuately forwardly extending upper ends secured to said side arms, tubular connecting braces between the lower ends of said arms and members, arcuate vertically spaced transversely extending tubular frame bracing members secured at their ends to said depending parallel side arms, an arcuate front panel supported by said last mentioned tubular frame bracing members, notched vertically spaced arcuate transversely extending golf club handle supporting strips secured to the upper and lower ends of said arcuate front panel, vertically spaced upper and lower platforms disposed at the lower ends of said arcuate front panel for respectively supporting metal head and wood head golf clubs when their shanks or handles are

received in said arcuate notched handle supporting strips on the front surface of said arcuate front panel, said panel having inverted V-shaped wood head positioning notches formed between said vertically spaced upper and lower platforms, upper and lower compartments supported by the carrier frame at the rear of said arcuate front panel, hinged closures for said compartments, and carrier supporting wheels detachably supported by said carrier frame.

5. The subject matter as claimed in claim 4, said carrier side frame members being formed with aligned bores, and said detachable wheels, having attaching means comprising arcuate heads engageable with the carrier frame and having spindles fixed thereto for inserting into said aligned bores.
